US00D902882S

(12) **United States Design Patent** (10) Patent No.: **US D902,882 S**
(45) Date of Patent: **** Nov. 24, 2020**

(54) **DIGITAL MEDIA PLAYER**

(71) Applicant: **NVIDIA Corporation**, San Jose, CA (US)

(72) Inventors: **Yongju Kwak**, San Jose, CA (US); **Boris Landwehr**, Thousand Oaks, CA (US); **Pei-Lin Lo**, Taipei (TW); **Andrew Robert Bell**, San Francisco, CA (US)

(73) Assignee: **NVIDIA Corporation**, Santa Clara, CA (US)

(**) Term: **15 Years**

(21) Appl. No.: **29/693,092**

(22) Filed: **May 30, 2019**

(51) LOC (12) Cl. **14-03**

(52) U.S. Cl. USPC **D14/203.6**; D14/496

(57) **CLAIM**

The ornamental design for a digital media player, as shown and described.

DESCRIPTION

FIG. 1 is a top view of the digital media player showing the design;

FIG. 2 is a bottom view thereof;

FIG. 3 is a front view thereof;

FIG. 4 is a back view thereof;

FIG. 5 is a right side view thereof;

FIG. 6 is a left side view thereof;

FIG. 7 is perspective view of the right side; and,

FIG. 8 is a perspective view of the left side.

The broken lines are directed to environment, represent unclaimed subject matter, and form no part of the claimed design.
